(57) **CLAIM**

An ornamental design for a vacuum cleaner canister, as shown and described.

DESCRIPTION

FIG. 1 is a perspective view of a vacuum cleaner canister showing my new design;

FIG. 2 is a top plan view thereof;

FIG. 3 is a right side elevation view thereof;

FIG. 4 is a left side elevation view thereof;

FIG. 5 is a rear elevation view thereof;

FIG. 6 is a front elevation view thereof; and,

FIG. 7 is a bottom plan view thereof.

Features shown in broken lines are shown for environment only and do not form a part of the design claimed.
